United States Patent Office

Des. 203,194

Patented Dec. 14, 1965

203,194

CHEST

Bert J. Klein and Andre Bus, Altavista, and John B. Thorn, Lynchburg, Va.

Filed Apr. 19, 1965, Ser. No. 84,849

Term of patent 14 years

(Cl. D33—6)

The single figure is a perspective view of a chest embodying our new design.

The side not shown is like the side shown while the back of the chest is plain and unornamented.

We claim:

The ornamental design for a chest, as shown and described.
